Primary Examiner—Raphael Barkai[57] **CLAIM**

The ornamental design for a walking attachment for in-line skate, as shown and described.

DESCRIPTION

FIG. 1 is a right side view of the walking attachment for in-line skate of the present invention;

FIG. 2 is a left side view thereof;

FIG. 3 is a front view thereof;

FIG. 4 is a rear view thereof;

FIG. 5 is a top view thereof; and,

FIG. 6 is a bottom view thereof.

The broken line showing of the name "blade walkers" is for illustrative purposes only and forms no part of the claimed design.
